CLAIM

We claim the ornamental design for a portable dialysis cabinet, as shown and described.

DESCRIPTION

FIG. 1 is a perspective view of a portable dialysis cabinet according to one embodiment;

FIG. 2 is a front view of the portable dialysis cabinet referenced in FIG. 1;

FIG. 3 is a rear view of the portable dialysis cabinet referenced in FIG. 1;

FIG. 4 is a left side view of the portable dialysis cabinet referenced in FIG. 1;

FIG. 5 is a right side view of the portable dialysis cabinet referenced in FIG. 1;

FIG. 6 is a top view of the portable dialysis cabinet referenced in FIG. 1; and,

FIG. 7 is a bottom view of the portable dialysis cabinet referenced in FIG. 1.
